SUPPORT FOR A PAINT BRUSH AND CLEANING VESSEL

William S. Montgomery, Jenkintown, Pa.

Application July 7, 1958, Serial No. 51,676

Term of patent 14 years

(Cl. D9—2)

FIG.1.

FIG.2.

FIG.3.

FIG.4.

Fig. 1 is a front perspective view of a support embodying my new design, showing the paint brush and cleaning vessel in broken lines for illustrative purposes only;

Fig. 2 is a rear perspective view of the support;

Fig. 3 is a front elevational view thereof, as shown in Fig. 1; and

Fig. 4 is a side elevational view thereof, as shown in Fig. 1.

I claim:

The ornamental design for a support for a paint brush and cleaning vessel, as shown and described.
